UNITED STATES PATENT OFFICE

GEORGE F. BURESH, OF CEDAR RAPIDS, IOWA

SAFETY DEVICE FOR AUTOMOBILES

Application filed September 14, 1929. Serial No. 392,542.

This invention relates to safety devices designed for use upon automobiles and pertains particularly to a device designed primarily to enable a rider of the vehicle to secure himself therein so that in the event of collision of the vehicle with another object the rider will not be thrown therefrom or thereabout.

The primary object, therefore, is to provide a device adapted for use by occupants of a vehicle whereby they will be prevented from falling or being thrown therefrom in the event that the vehicle is subjected to any severe shocks or jars.

The invention broadly contemplates the provision of a strap having snap buckles at each end, one of the snaps being adapted for connection with an eye bolt secured to the vehicle seat, preferably to the back thereof at the top while the other snap is provided for connection with an eye secured at the base of the seat back. The strap is thus secured vertically across the seat and adjacent its upper end has attached thereto an adjustable loop through which the arm of an occupant of the seat may be extended to position it across the said occupant's shoulder, or it may be grasped by the hand.

The invention will be best understood from a consideration of the following detailed description taken in connection with the accompanying drawings forming a part of the present specification with the understanding, however, that the invention is not confined to any strict conformity with the showing of the drawing but may be changed or modified so long as such changes or modifications mark no material departure from the salient features of the invention, as expressed in the appended claims.

In the drawings:—

Figure 1 is a transverse sectional view of the vehicle seat and back showing the application of the safety strap embodying the present invention.

Figure 2 is a view in front elevation of the strap, per se.

Figure 3 is a sectional view taken upon the line 3—3 of Figure 2.

Figure 4 is a plan view of a three bar buckle showing the formation of teeth thereon.

Referring more particularly to the drawings wherein like numerals of reference indicate corresponding parts throughout the several views, the present motor vehicle safety device is shown as attached to a seat of ordinary construction. The seat is indicated generally by the numeral 1, the bottom cushion thereof being indicated at 2 and the back cushion at 3, the frame for the back cushion being indicated generally by the numeral 4 and the top and bottom rails thereof by the numerals 5 and 6 respectively.

The device embodying the present invention comprises a strap 7 which is preferably formed in one piece throughout. At one end this strap is turned back to form the loop 8, the body portion thereof being passed between the side bars 9 of a three bar buckle 10 and over the center bar 11 thereof in the manner shown, the terminal portion being brought back over the face of the body and also passing under the two side bars of this buckle and over the center bar to form the loop 8.

This loop 8 at the bottom of the holding device engages through an elongated metal loop 12 to the central portion of which is swivelly attached a snap buckle 13. This snap buckle engages the eye of a suitable screw or bolt 14 which is secured vertically in the bottom rail 6 of the seat back frame. By sliding buckle 10 up or down on the body of strap 7, the same may be shortened or lengthened.

The strap 7 after being secured at one end in the manner described to the lower part of the seat back is passed up over the face of the seat back and extended through the metal loop 15 of a second snap buckle 16, this loop

being swivelly attached to the buckle as shown. This upper snap buckle 16 engages a bolt 17 which extends horizontally through the top portion 5 of the seat back frame extending forwardly from the top of the seat back as shown in Figure 1. After passing through the eye 15 of the snap buckle 16 the strap is extended down and attached at its other end to that portion overlying the central part of the seat back by means of a three bar buckle 18 similar to the buckle 10. As shown this buckle 18 has the main body portion of the strap 7 passing under the two side bars thereof and over the center bar and the upper end 19 of the strap is also passed therethrough in this manner so as to form the loop 20 through which the occupant of the seat may extend his or her arm.

In order to hold the upper lapped part of the strap in the proper position two resilient bands 21 are passed thereabout, one of these bands being shown in detail in Figure 3 and as is also clearly shown in this figure each of the long side bars of the band 21 is toothed upon its inner face, the teeth being indicated by the numerals 22.

The under face of each of the side bars of the buckles 10 and 18 is also provided with teeth as indicated at 23 and the top or outer side of the central bar of each of these buckles has the teeth 24 formed thereon so that it will be readily seen that the buckles will be securely held in engagement with the straps passed therethrough so that accidental slipping and enlarging of the loop 18 or of the loop 8 will be prevented.

It will be readily seen that by sliding the buckle 18 up or down upon the body of the strap 7 and by drawing the end 19 therethrough in the proper direction the loop 20 may be enlarged or made smaller as desired without disturbing the connection between the turned upper and lower portions of the strap and the snap fasteners by means of which the strap is held in position.

The purpose of the resilient bands 21 in addition to keeping the strap from sliding back and forth on loop 15 is to allow for adjustments of the loop 20, that is, permitting the loop to be increased or decreased in size without disturbing the buckle 18 which secures the end of this loop to the main body portion of the strap. As will be readily seen by slipping the lower one of the bands 21 up or down the size of the loop 20 can be regulated without shifting the more difficultly movable buckle 18.

While I have particularly shown the present safety device in connection with a front seat back and shown the same extending vertically thereacross it is, of course, to be understood that I do not wish to be limited in any manner to the use of this strap for it will be obvious that the same may be arranged in a number of different positions

over the seat back and it may also be used in connection with a rumble seat by being positioned across the back thereof or extended from the top forwardly for engagement with a portion of the machine body so that it will be positioned at the rider's side where the loop 20 may be grasped or the arm of the rider may be extended therethrough.

Having thus described my invention, what I claim is:—

1. A safety device for attachment to seats, comprising a strap having one end turned back and secured to form a loop, a snap fastener engaged by said loop and designed to engage a fixed element adjacent the seat, a second snap fastener having the median portion of the strap adjustably engaged therewith and designed for engagement with a fixed member remotely positioned from the first mentioned member, and a buckle adjustably carried by the strap between said snap fasteners, said strap having its other end engaged through said buckle and adjusted to form a loop adapted to be grasped by an occupant of the seat.

2. A safety device for attachment to seats, comprising a strap having one end turned back and secured to form a loop, a snap fastener engaged by said loop and designed to engage a fixed element adjacent the seat, a second snap fastener having the median portion of the strap adjustably engaged therewith and designed for engagement with a fixed member remotely positioned from the first mentioned member, a buckle adjustably carried by the strap between said snap fasteners, said strap having its other end engaged through said buckle and adjusted to form a loop adapted to be grasped by an occupant of the seat, and adjustable fastening bands surrounding the superposed portions of the strap adjacent the second mentioned buckle.

3. A safety device for attachment to seats, comprising a strap having a loop formed at one end, a snap fastener engaged by said loop and designed to engage a fixed element adjacent the seat, a second snap fastener having engagement with the strap at the median portion thereof and designed for engagement with a fixed member remotely positioned from the first mentioned member, and a buckle carried by the strap between said snap fasteners, said strap having its other end engaged through said buckle and adjusted to form a loop adapted to be grasped by an occupant of the seat.

4. A safety device for attachment to seats, comprising a strap, means carried by the strap at one end for connection with a fixed portion of the seat, means adjustably attached to the strap adjacent the median portion thereof and engaged with a fixed member remotely positioned from the fixed end of the strap, a fastening element carried by

the strap between the first mentioned means and the adjustable means for engaging and securing the other end thereto to form a loop adapted to be grasped by an occupant of the seat.

5 In testimony whereof I hereunto affix my signature.

GEORGE F. BURESH.
